UNITED STATES PATENT OFFICE

139,875

DESIGN FOR A FILTER FOR WELDING MACHINES

Raymond J. Breckheimer, Milwaukee, Wis., as-
signor to Badger Manufacturing & Sales Com-
pany, Milwaukee, Wis.

Application September 2, 1944, Serial No. 115,173

Term of patent 14 years

(Cl. D62—2)

To all whom it may concern:

Be it known that I, Raymond J. Breckheimer, a citizen of the United States and resident of Milwaukee, in the county of Milwaukee and State of Wisconsin, have invented a new, original, and ornamental Design for a Filter for Welding Machines, of which the following is a specification, reference being had to the accompanying drawing, forming part thereof.

Figure 1 is a side elevational view of a filter for welding machines showing my new design.

Figure 2 is a front elevational view of my filter.

I claim:

The ornamental design for a filter for welding machines, as shown.

RAYMOND J. BRECKHEIMER.
